UNITED STATES PATENT OFFICE.

ANDREW JENSEN AND WILLIAM REISSNER, OF DES MOINES, IOWA.

COUNTER-REFRIGERATOR.

SPECIFICATION forming part of Letters Patent No. 732,945, dated July 7, 1903.

Application filed November 4, 1901. Serial No. 81,047. (No model.)

To all whom it may concern:

Be it known that we, ANDREW JENSEN and WILLIAM REISSNER, citizens of the United States of America, and residents of Des Moines, in the county of Polk and State of Iowa, have invented a new and useful Counter-Refrigerator, of which the following is a specification.

This invention relates to the type of devices illustrated by Letters Patent of the United States No. 673,921, granted May 14, 1901, to James P. Nelsen, Andrew Jensen, and William Reissner, and is an improvement on the structure defined in said patent.

The object of this invention is to provide improved means for lowering the temperature of the atmosphere within and cooling the contents of a show-case or counter, to the end that fresh meats, fruits, and vegetables may be exhibited to the inspection of prospective purchasers and yet retained under refrigeration.

Our invention consists of the construction, arrangement, and combination of elements hereinafter set forth, pointed out in our claims, and illustrated by the accompanying drawings, in which—

Figure 1 is a perspective of our improved counter-refrigerator, one corner of the casing being broken away to reveal the interior construction. Fig. 2 is a longitudinal vertical section of our improved device. Fig. 3 is a cross-section on the indicated line 3 3 of Fig. 3. Fig. 4 is a plan of one of the ice-supporting air-chambers employed in our device.

In the construction of the device as shown the numeral 10 designates a counter formed with double or triple side walls, top, ends, and bottom designed to render the contents thereof less susceptible to the influence of exterior temperature. A partition 11 is mounted vertically and transversely in one end portion of the counter 10 and forms a small chamber at one end of the counter and a large chamber extending from the partition to the opposite end of the counter. A door 12 in one end of the counter 10 provides access to the interior of the small chamber and a door 13 in the opposite end of said counter provides access to the interior of the large chamber. A show-case 14, composed of a framework fitted with sheets of glass and doors 15

16, is mounted on the counter 10 and secured thereto. The glass portions of the show-case 14 are three-ply—that is to say, three sheets of glass 17 18 19 are mounted parallel with each other and spaced apart to form two air-chambers and protect the contents of the show-case against the influence of exterior temperature and, further, to avoid condensation or moisture on either glass plate. A pan 20, preferably made of sheet metal, is mounted on the floor of the large chamber of the counter and is provided with a drainage-pipe 21, leading through the floor or wall of the counter and arranged to carry away water from the ice melting in said chamber. An air-chamber 22 is mounted in the pan 20 and comprises, Fig. 4, end pieces 23 24, side pieces 25 26, and top and bottom sheets 27 28, respectively, of sheet metal. The sheets 27 28, forming the top and bottom of the air-chamber 22, are tacked or otherwise firmly secured to the top and bottom edges, respectively, of the end and side pieces, and the margins of the top sheet 27 are turned upward to form a pan. Between the side pieces 25 26 of the air-chamber are partitions formed of slats or strips 29 30 31 32 33, to which the top and bottom sheets 27 28 also are secured. The partitions or strips in the air-chamber are of less length than the side strips 25 26. The partitions 29 31 33 abut at one end the inner surface of the end piece 24 of the air-chamber and the partitions 30 32 abut at one end the inner surface of the end piece 23 of the air-chamber, thus providing, the partitions being spaced apart, a sinuous passage 34 for air within the chamber, as indicated by the arrows in Fig. 4. An exhaust-fan 35 is mounted in the smaller chamber of the counter and driven by an electric motor 36 or other power, and a discharge-pipe 37 leads from said fan to and communicates with the initial end of the sinuous passage 34 of the air-chamber. The connection between the terminal of the discharge-pipe 37 and the initial end of the air-passage is detachable, since the pipe is loosely introduced in the air-passage after passing through the partition 11. Cleats 38 39 are mounted longitudinally of the side walls of the counter 10 within the larger chamber thereof, and an air-chamber 40, in construction alike with the air-chamber 22, is mounted

on said cleats. An air-pipe 41 is mounted vertically in the smaller chamber of the counter 10 and has its end portions curved and extending through the partition 11. The 5 lower end portion of the air-pipe 41 is introduced loosely into and communicates with the terminal of the air-passage 34 of the chamber 22, and the upper end of said pipe is introduced loosely to and communicates with 10 the initial end of a like sinuous air-passage in the chamber 40. An air-pipe 42 is mounted vertically in the smaller chamber of the counter, with one end portion curved and extended through the partition 11. The lower 15 end portion of the air-pipe 42 is introduced loosely into and communicates with the terminal of the sinuous air-passage of the chamber 40 and the upper end portion of said pipe extends through the floor of the show-case 20 and communicates with the interior thereof. An air-pipe 43 is mounted vertically in that end portion of the show-case opposite the air-pipe 42 and leads from a point near the lower surface of the top of the show-case through 25 the floor thereof and communicates with the interior of the larger chamber of the counter 10. The ingress-pipe 44 of the air-pump 35 leads from that end portion of the larger chamber of the counter opposite to the air-pipe 43, extends through the partition 11, is 30 curved, and enters the shell of the fan axially.

On reference to Fig. 4 it will be observed that corner-blocks 45 are mounted in the sinuous passage 34 of the air-chamber 22, and the 35 inner edges of said corner-blocks are curved and so fitted together as to round the bents or returns of said air-passage, thus providing the minimum of friction to the travel of air therethrough. Cakes 46 of ice are mounted 40 on the upper sheet 27^a of the air-chamber 40, and the water produced by the melting of such cakes of ice drains from the pan formed by said upper sheet and into the pan 20, from whence it flows through the pipe 21. Cakes 45 47 of ice are mounted on the upper sheet 27 of the air-chamber 22, and the water formed by the melting of such cakes drains from the pan formed by said upper sheet into the pan 20, from whence it flows through the pipe 21. 50 The doorway of the door 13 opens to the bottom of the counter-chamber and either of the air-chambers, and the pan 20 may be withdrawn longitudinally through said doorway at any time. In the withdrawal of the air-chambers through the doorway said chambers 55 easily detach from the end portions of the air-pipes 37, 41, and 42.

In practical use the exhaust-fan draws the air from the ice-chamber through the ingress-60 pipe 44, and air enters said ice-chamber through the pipe 43 from the show-case 14 and circulates around and among the cakes 46 47 of ice. The discharge-pipe 37 leads the air from the exhaust-fan into and the same is 65 forced through the sinuous passage 34 of the air-chamber 22. The pipe 41 leads the air from the chamber 22 to the chamber 40, and said

air is forced through the sinuous passage of said chamber, and the air-pipe 42 leads said air from the chamber 40 into the show-case. 70 The top and bottom of the chamber 22 and the chamber 40 being made of sheet metal and the top sheets carrying the cakes of ice, it follows that in the travel of the air through the sinuous passages of the air-chambers it 75 becomes thoroughly cooled by the proximity of the ice and the cooling influence thereof radiated through said top sheets. Hence when the air enters the show-case at the terminal of the pipe 42 the temperature thereof is reduced a considerable extent. When the temperature of the contents of the show-case have been reduced to the desired extent, there is little or no waste of ice arising from the circulation of air, since there is comparatively 80 little communication between the interior and exterior of the show-case or counter. Further increase of temperature will arise from time to time in the opening of the doors 15 16, but will be readily neutralized by the cooling 85 influence of the air constantly circulated through the sinuous passages of the air-chambers into and from the show-case. The partition 11 serves the useful function of dividing the counter into two chambers and at the 90 same time removing or partitioning the ice from the heating influence of the motor and fan bearings.

We claim as our invention—

1. In a display-refrigerator, the combination of a counter formed with a larger and a smaller chamber, an air-chamber mounted in the bottom of the larger chamber and arranged to support ice, an air-chamber mounted across the central portion of the larger chamber and arranged to support ice, a door in one end of the larger chamber whereby access is had thereto, a show-case mounted on the counter, an open-ended pipe mounted vertically through the top of the counter and extended nearly to the top of the show-case, an exhaust-fan mounted in the smaller chamber of the counter, an ingress-pipe leading from the larger chamber of the counter to said exhaust-fan, a discharge-pipe leading from the exhaust-fan to the lower air-chamber, a pipe leading from the lower air-chamber to the upper air-chamber, a pipe leading from the upper air-chamber to the show-case and a door opening to the smaller chamber of the counter. 100

2. In a display-refrigerator, the combination of the counter formed with an ice-chamber and a power-chamber, a door forming one end of the ice-chamber and providing access thereto, a pan mounted on the bottom of the ice-chamber and removable longitudinally therefrom, an air-chamber mounted in said pan, an air-chamber mounted across the ice-chamber above the first air-chamber and removable and replaceable longitudinally, the show-case on the counter, air communication between the show-case and ice-chamber, pipes connecting the air-chambers and connecting 105 110 115 120 125 130

one air-chamber with the show-case, a driven exhaust-fan in the power-chamber and air communication between said fan and the ice-chamber and between said fan and the lower chamber, together with a door providing access to the power-chamber.

3. In a display - refrigerator, a counter formed with an ice-chamber and a power-chamber, air-chambers removably and ⁵ placeably mounted horizontally across the ice-chamber, each of which air-chambers is formed with a sinuous passage and arranged to support ice, a show-case surmounting the counter, air communication between the show-¹⁰ case and ice-chamber, a fan in the power-chamber, air communication between the ice-chamber and fan, air communication between

the fan and one end of the sinuous passage of the lower air-chamber, air communication between the other end of said sinuous passage ²⁰ and one end of the sinuous passage of the upper air-chamber, air communication between the other end of the sinuous passage of the upper air-chamber and the show-case and means of access to the show-case and power-²⁵ chamber.

In testimony whereof we hereunto have set our hands, at Des Moines, Iowa, this 6th day of July, 1901, in the presence of two witnesses.

ANDREW JENSEN.

WILLIAM REISSNER.
